UNITED STATES PATENT OFFICE.

ROBERT A. WILSON, OF DALLAS, TEXAS, ASSIGNOR TO THE GUIBERSON CORPORATION, OF DALLAS, TEXAS, A CORPORATION OF DELAWARE.

AUTOMATIC TUBING CATCHER FOR WELLS.

Application filed June 26, 1926. Serial No. 118,633.

This invention relates to new and useful improvements in automatic tubing catchers for wells.

The invention has to do with that type of catcher in which slips are automatically displaced into engagement with the walls of the casing when the tubing to which the catcher is attached, is dropped or falls.

The object of the invention is to provide a catcher in which the actuating weight member is sustained by elastic means, other than a spring, and said elastic means being normally under tension by extension; whereby upon a fall or drop of the catcher, the inertia of the weight will relieve the tension of said elastic means and cause the slips to set.

A construction designed to carry out the invention will be hereinafter described together with other features of the invention.

The invention will be more readily understood from a reading of the following specification and by reference to the accompanying drawings, in which an example of the invention is shown and wherein:

Fig. 1 is an elevation of a tubing catcher constructed in accordance with my invention,

Fig. 2 is a horizontal cross-sectional view taken on the line 2—2 of Fig. 1, and

Fig. 3 is an enlarged vertical sectional view taken on the line 3—3 of Fig. 1.

In the drawings the numeral 10 designates a section of well tubing having a collar 11 at its upper end and a collar 12 at its lower end. A head 13 is immovably secured on the tubing below the collar 11. The head is formed from a cylindrical body and has a reduced collar 14 at its upper end surrounding the tubing. Three downwardly and inwardly inclined guide faces 15 are equally spaced on the sides of the head. A guide rib 16 extends down the center of each face. Each guide rib is dovetailed in cross section.

On each face is mounted a gripper slip 17 having its inner side or back flat so as to lie against and slide upon the guide face 15. The outer side or front of the slip is curved transversely in an arc concentric to the tubing and is provided with the usual gripper teeth 18. Each slip is also given a wedge shape, being reduced from its bottom to its top edge. It is preferable to give the back of the slip the same angle of inclination as

the face 15 and to make the point of the slip on the same radius throughout, thereby holding the teeth parallel to the inner wall of the casing at all elevations of adjustment.

Each slip is formed with dovetailed recess 19 complementary to and receiving the guide rib 16. By this arrangement each slip is free to slide vertically, but is held against relative outward displacement and the equal spacing of the slips is also maintained. Each slip has a pair of spaced ears 20 on its bottom and the upper end of a link 21 is pivoted between said ears. At the bottom of each guide face the head has a boss 22 provided with a central slot 23 through which the link depends. The guide ribs 16 terminate at the slots. The outer faces of the boss may conform to the curvature of the head proper. The head is provided with concaved vertical channels 24 between the guide faces 16 permitting a free passage of fluid.

A cylindrical weight member 25 is mounted to slide freely on the tubing section 10. There should be ample clearance between the bore of the member and the tubing section to permit the tubing to move freely down through said member. The member may have one or more sand and oil bleed ports 26 and both its lower and upper ends are preferably beveled.

The upper end of the weight member is provided with spaced ears 27 between which the lower ends of the links 21 are pivoted. At the lower ends of the channels 24 I provide sumps 28, while directly below, notches 29 are formed in the upper end of the weight member. Links or straps 30 of rubber or other elastic material, having rounded ends 31, are secured in the sumps and notches by machine screws 32.

The weight member is thus initially sustained by the straps 30, but it is heavy enough to stretch said straps and thus place them under tension. The downward movement of the member 25 is limited by the collar 12 and the contact therewith takes some of the strain off of the straps. This may also be accomplished by allowing the ears 20 to rest on the bosses 22, when the straps are tensioned.

In using the catcher it is connected in the string of tubing by means of the collars 11 and 12, the nearer the bottom the better, but always within the casing. Normally the

slips will be withdrawn within the diameter of the head 13, and the teeth thereof will not engage the casing (not shown), thus permitting the catcher to be freely moved 5 up and down in the casing with the string of tubing.

If the string of tubing should break at any point above the head 13 or if the string should be dropped, the operation will be as 10 follows: The inertia of the weight member 25, accentuated by the tendency of the elastic straps 30 to retract, will cause said weight member to momentarily remain relatively stationary, thus maintaining its position. 15 The head 13 and tubing section 10, however, being attached to the string of moving tubing will tend to descend more rapidly and consequently the links 21 being sustained by the inert member 25, will support the 20 slips 17. This will result in an outward or radial displacement of the slips on the guide faces 15 of the head, whereby the teeth 18 will bite into the casing and hold the parts suspended against a further drop. This action 25 is very rapid and the catch is usually made within a few inches.

Various changes in the size and shape of the different parts, as well as modifications and alterations, may be made within the 30 scope of the appended claims.

What I claim, is:

1. In an automatic well tubing catcher, a tubing section, a head connected therewith, gripper slips mounted on the head and movable outwardly relatively of the head, a 35

weight member slidable on the section below the head, connections between the slips and said member, and elastic connections between the head and weight member of rubber-like material of sufficient rigidity to resist retraction when distended to suspend said member. 40

2. In an automatic well tubing catcher, a tubing section, a head connected therewith, gripper slips mounted on the head and movable outwardly relatively of the head, a weight member slidable on the section below the head, connections between the slips and said member, and elastic straps of rubber-like sheet material of sufficient rigidity 45 to resist retraction when distended to suspend said member and secured at their opposite ends to the outer face of the head and weight member. 50

3. In an automatic well tubing catcher, a tubing section, a head connected therewith and having recesses at its lower edge, gripper slips mounted on the head and movable outwardly relatively of the head, a weight member slidable on the section below the head and having recesses at its upper edge, connections between the slips and said member, and straps of elastic rubber-like material having their upper ends attached within the recesses at the lower end of the head and 60 their lower ends attached within the recesses at the upper end of the weight member and tensioned by the latter. 65

In testimony whereof I affix my signature.

ROBERT A. WILSON.
